UNITED STATES PATENT OFFICE.

WILLIAM S. SMITH, OF CAMBRIDGE, MASSACHUSETTS.

ALTERNATING-CURRENT MAGNET.

1,222,900.

Specification of Letters Patent.

Patented Apr. 17, 1917.

Application filed September 10, 1915. Serial No. 49,954.

To all whom it may concern:

Be it known that I, WILLIAM S. SMITH, a citizen of the United States, residing at Cambridge, in the county of Middlesex and 5 State of Massachusetts, have invented a new and useful Improvement in Alternating-Current Magnets, of which the following is a specification, reference being had therein to the accompanying drawings.

10 This invention relates to an alternating current magnet.

Heretofore it has been customary in magnets of this character, to make the magnet frame and core in laminated sections; that 15 is, thin metallic plates bound together, in order to prevent the excessive heating which the high magnetic density of a solid frame and a solid core entails. This construction is expensive and is mechanically poor. The 20 laminations are apt to become loosened causing the magnet to become noisy and hum. When so made the cores are generally square or rectangular in cross-section and it is necessary to provide angular corner pieces as 25 guides to their movements. This construction, however, renders smooth bearing surfaces impracticable so that the magnet is generally noisy in operation. The use of 30 tubes of non-conducting material as bearings for the cores have been contemplated but such tubes soon become warped and get out of shape and moreover do not form good bearing surfaces for the cores.

The main object of my invention is to 35 provide an alternating current magnet which is quiet in operation and to this end I provide a guide tube for the core which is so constructed that the heating due to eddy currents, is practically eradicated.

40 A further object of my invention is to provide means whereby the movement of the core may be regulated to a fine degree in order to reduce the noise of operation of the magnet to a minimum and to increase its 45 efficiency.

An additional object is to provide means whereby a good contact is always secured.

Other objects of the invention are to increase the efficiency of the magnet and to 50 reduce the cost of manufacture.

In the accompanying drawings I have shown my invention as embodied in a two pole circuit closer or contactor and Figure 55 1 is a front elevation of such an apparatus constructed and operated in accordance with my invention; Fig. 2 is a side elevation of

the same; Fig. 3 is a central vertical sectional view of the magnet; Fig. 4 is a front elevation of the same; Fig. 5 is a horizontal sectional view on line 5—5 in Fig. 3; Fig. 6 60 is an end view of the core; Fig. 7 is a side elevation of the core looking from left to right in Fig. 6; Fig. 8 is a side elevation of the same turned ninety degrees from Fig. 7; Fig. 9 is a plan view of the core bracket; Fig. 65 10 is a side elevation of the core bracket; Fig. 11 is a side elevation of the same turning Fig. 10 ninety degrees; Fig. 12 is a front elevation of the movable arm carrying the contact plates; Fig. 13 is a side elevation of the same; Fig. 14 is a side elevation of the toggle joint; Fig. 15 is a side elevation of the other toggle joint; Fig. 16 is a plan view of the other toggle joint and Fig. 17 is a side elevation of a stationary contact 75 piece.

In the drawings illustrating one application of my invention is shown a two pole circuit closer or contactor in which 20 is a supporting base of insulating material upon 80 which is mounted the magnet comprising a magnet frame 21, a coil 22 and a core 23 mounted within a guide tube 24. The magnet circuit is designated 25.

In order to prevent eddy currents and consequent heating while retaining a solid construction, the frame 21 is split from the center to the rear so as to form two wings 26 and 27, each of which is provided with a vertical extension 28 bored at 29 to receive a 90 bolt 30 by means of which the magnet frame is attached to the supporting base 20. (See Figs. 3-5.) The space separating the two wings is shown in the drawings at 31 and this space suffices to prevent the circulation 95 of eddy currents. The frame may be made in any suitable shape or form so long as this feature is retained.

In the core I prefer to retain the old construction of laminated sections 32 bound together by bolts 33 (see Figs. 6, 7 and 8) but the core is substantially circular in cross-section except where flattened on two sides to permit the bolts to be headed. Secured to the magnet frame and within the coil is arranged the guide tube 24 in one piece but provided with a longitudinal slot 34. The tube and core are of such relative dimensions that the core fits the tube closely to avoid vibration and yet not so closely as to 110 develop friction to retard the longitudinal movement of the core in the tube when the

magnet is energized or deenergized. The guide tube and frame are so arranged that the slot 34 in the guide tube is in alignment with the space 31 between the two wings of 5 the frame.

The core 23 is fixedly mounted in a bracket (see Figs. 9-11) having a collar portion 35 and two downwardly projecting lugs 36 each having a hole 37 to receive a bolt or 10 pin whereby the bracket may be connected to arms or levers to be operated by the movement of the core. The lower portion of the frame 21 is provided with a depending extension 38 having a recess 39 adapted to 15 receive the bracket 35 the inner surface 40 of said recess forming a bearing surface for the bracket and also serving as a guide for the same. (Fig. 3.)

In the top of the magnet frame and extending 20 into the top of the guide tube 24 is an adjusting screw 41 held in any adjusted position by a set-nut 43. This screw limits the upward movement of the core when the magnet is energized. (See Fig. 3.)

Although the magnet is susceptible of various uses it is illustrated as operating a two pole circuit closer or contactor. Fulcrumed at 45 on the frame is a yoke lever 46 (Figs. 12 and 13) its upper ends each 25 carrying a contact piece 47 connected in a circuit 48 and insulated from the yoke lever by non-conducting material 49. The lower end of the yoke lever is connected to the core bracket by a toggle joint lever made up 30 of two links 50, (Fig. 14) and 51 (Figs. 16 and 17). The latter is pivotally mounted on the lower portion of the frame at 52 and its free end is provided with a slot 53 through which passes a pin 54 mounted in 35 the lugs 36 of the core bracket. The link 50 connects the lower end of the yoke lever with the link 51. The outward movement of the yoke lever is limited by a rubber stop 55 on the frame extension 38.

Coöperating with the movable contacts 47 on the yoke lever 46 are fixed contacts 56 each mounted on a support 57. (See Fig. 17.) For the purpose of securing a good flat contact between each pair of contact 50 pieces when operative, the contact 56 may be mounted on a plate 58 which is loosely mounted on two pins 59 carried by a plate 60 on the supporting member 57. Cotter pins 61 hold the plate 58 on the pins 59 and 55 two helical springs 62 one on each pin 59 serves to keep the plate 58 and contact member 56 in a forward position at all times. This construction permits of a limited movement of the contact member in all directions and has the effect of a universal joint.

The operation of the magnet is as follows. The magnet circuit 25 is controlled by any suitable form of switch not shown. When the switch is open, the magnet circuit 25 is 60 open and the magnet is deenergized and the

parts are in the position shown in Figs. 1, 2 and 3. The closing of the magnet circuit, however, energizes the magnet thereby causing the core to be drawn upwardly until it reaches the end of its movement.

As the core is drawn upwardly the lower end of the yoke lever is thrown outwardly through the medium of the links 50 and 51 thereby causing the upper end of the yoke lever to be thrown inwardly and the contacts 70 47 to engage the contacts 56 and to close the circuit 48 which may be either direct or alternating. By having the stationary contacts 56 mounted on springs I secure a limited pivotal movement of the same which 75 insures a full contact; that is, the contact 47 engages the contact 56 on its entire face. At the same time the springs 62 permit the screw 41 to be adjusted to limit the movement of the core in the magnet without 80 affecting the contact. So long as the magnet circuit 25 is closed the magnet remains energized and retains the yoke lever in the position of closing the circuit 48. When, however, the magnet circuit is broken and the 85 magnet deenergized, the core drops by force of gravity thus causing the upper end of the yoke lever to move outwardly and to break the circuit 48. The compression of the springs 62 assists this movement by forcing 90 the upper end of the yoke lever outwardly.

In the operation of the magnet the arrangement of the two links 50 and 51 is an important feature. The link 51 is pivotally connected to the magnet frame at 52, which 95 is a fixed point and is pivotally connected to the link 50 at 70 which is a movable point. The other end of the link 50 is connected to the yoke lever 46 at point 71 which is also a movable point. In Fig. 2, which 100 shows the core 23 in its lowest position, the point 70 is below the points 71 and 52. When the magnet is energized the core is drawn upwardly, which raises the point 70 throwing the point 71 outwardly and, to a 105 slight degree, lowers it, the point 52 remaining fixed. When the magnet is deenergized the force of gravity causes the core to drop and the springs 62 assist in this action by pressing the upper portion 110 of the yoke lever outwardly. If the movement of the core 23 is great enough to raise the point 70, when the magnet is energized, into or above the horizontal plane in which the points 71 and 52 lie, then it will be apparent that as soon as the magnet is deenergized the action of the force of gravity 115 upon the core may not be sufficient to cause it to drop and the core may remain in its upper position and the circuit 48 remain 120 closed. It is important, therefore, that the point 70 should, when the magnet is energized, be below the horizontal plane passing through the points 71 and 52 and in order to reduce the noise of operation to a 125 130

minimum, this point should be capable of fine adjustment. If the point 70 is too far below the points 71 and 52 when the magnet is energized a loud humming noise will 5 ensue, due to the fact that as the current in the circuit 25 fluctuates the core drops when the current weakens and is drawn back as the current increases in strength. These fluctuations being extremely rapid 10 result in a vibration of the core and produce a humming noise.

It is important, therefore, that the movement of the core should be subject to control to a fine degree and the adjustment 15 screw 41, which is one of the most important features of this invention, enables me to accomplish this result. By turning it to the right or left I can decrease or increase the length of the movement of the core and 20 I have found from actual experience that I can almost entirely eradicate the humming noise by making proper adjustments of this screw. Further, if there is a slight variation between different magnets I have found 25 that these variations can be overcome by making proper adjustments of the screw 41.

By constructing the magnet frame with the slot 31, in order to break up eddy currents and to prevent consequent heating of 30 the frame, I am thereby enabled to use a solid construction whereas heretofore it has been customary to make the frame in laminated sections. The solid construction can be made at a very much reduced cost, is permanent, does not become loosened by vibration or wear and enables perfect bearing 35 surfaces for the core and for the core bracket to be secured and, at the same time, permits the guide tube to be tightly fitted in 40 the frame. Again, the frame being of solid construction may be larger in cross-section in order to reduce the magnetic density.

Another important feature of my invention resides in the slotted guide tube for the 45 core. Heretofore, so far as I am aware, it has been impossible to use a metal guide tube for the core because of the excessive heating, due to eddy currents, which affected the magnet coil and caused rapid 50 deterioration of the magnet coil. By employing a metallic guide tube which is not subject to excessive heating, I am enabled to secure a smooth bearing surface in which the core may be well fitted in order to avoid 55 vibration and noise. This also enables me to turn the core in a lathe and reduces the cost of construction.

Although I have shown my invention as applied to one particular use, namely, in a 60 two pole circuit closer, it may be applied to various other uses to which a magnet of this character can be adapted. It is further to be observed that my invention may be embodied in other forms of construction 65 than that herein shown and described and I

desire to claim it broadly except where specifically limited in the following claims.

What I claim is:—

1. An alternating current magnet comprising a coil, a core, adjustable means forming part of the magnetic circuit for limiting the movement of the core when energized and means whereby the adjustment of said adjustable means regulates the amount of pull of the load upon said core. 75

2. An alternating current magnet comprising a coil, a core, adjustable means adapted when said core is energized to be in magnetic seal therewith and to limit its movement and means whereby the adjustment of said adjustable means regulates the amount of pull of the load upon said core. 80

3. An alternating current magnet comprising a coil, a core, adjustable means for limiting the movement of the core when energized and for regulating the length of the air gap when said core is not energized and means whereby the adjustment of said adjustable means regulates the amount of pull of the load upon said core. 85

4. An alternating current magnet comprising a coil, a core, adjustable means for regulating simultaneously the movement of the core when energized and the length of the air gap when the core is not energized and means whereby the adjustment of said adjustable means regulates the amount of pull of the load upon said core. 90

5. An alternating current magnet comprising a coil, a core, an adjustable screw forming part of the magnetic circuit for 100 limiting the movement of the core when energized and means whereby the adjustment of said adjustable means regulates the amount of pull of the load upon said core. 105

6. An alternating current magnet comprising a coil, a core, an adjustable screw adapted when said core is energized to be in magnetic seal therewith and to limit its movement and means whereby the adjustment of said adjustable means regulates the amount of pull of the load upon said core. 110

7. An alternating current magnet comprising a coil, a core, an adjustable screw for limiting the movement of the core when energized and for regulating the length of the air gap when said core is not energized and means whereby the adjustment of said adjustable means regulates the amount of pull of the load upon said core. 115

8. An alternating current magnet comprising a coil, a core, an adjustable screw for regulating simultaneously the movement of the core when energized and the length of the air gap when the core is not energized and means whereby the adjustment of said adjustable means regulates the amount of pull of the load upon said core. 120

9. An alternating current magnet comprising a coil, a core, an operating member 125

connected to said core and adapted to be moved thereby when said core is energized, means in magnetic circuit with said core and sealed thereto when said core is energized, said means being adjustable in order to prevent the breaking of said seal between the impulses of the current exciting said magnet and means whereby the adjustment of said adjustable means regulates the amount of pull of the load upon said core.

10. An alternating current magnet comprising a coil, a core, means connecting said core with its load, said means being so constructed that the pull on said core due to its load varies with the position of said core and means constituting part of the magnetic circuit for regulating the movement of the core when energized; said means being adjustable so that the movement of the core due to its load between the impulses of the current exciting the magnet may be regulated.

11. An alternating current magnet comprising a coil, a core, means connecting said core with its load, said means being so constructed that the pull on said core due to its load varies with the position of said core and adjustable means whereby the movement of the core due to said load between the impulses of the current exciting the magnet may be regulated.

12. An alternating current magnet comprising a coil, a core, adjustable means for regulating the amount of movement of the core when the magnet is energized and means whereby the adjustment of said adjustable means regulates the amount of pull of the load upon said core.

13. An alternating current magnet comprising a coil, a core, adjustable means for regulating the amount of movement of the core when the magnet is energized and positive means for returning the core to its normal position when the magnet is deenergized.

14. An alternating current magnet comprising a coil, a core, adjustable means for regulating the amount of movement of the core when the magnet is energized, means whereby the adjustment of said adjustable means regulates the amount of pull of the load upon said core and positive means for returning the core to its normal position when the magnet is deenergized.

In testimony whereof, I hereunto set my hand in the presence of two subscribing witnesses, this the nineteenth day of August, 1915.

WILLIAM S. SMITH.
